UNITED STATES PATENT OFFICE.

SIMEON S. JACKSON, OF BOSTON, MASSACHUSETTS, ASSIGNOR TO THE STAFFORD COMPANY, OF READVILLE, BOSTON, MASSACHUSETTS, A CORPORATION OF NEW JERSEY.

WEFT-REPLENISHING LOOM.

1,394,175.

Specification of Letters Patent.

Patented Oct. 18, 1921.

Application filed December 22, 1920. Serial No. 432,443.

To all whom it may concern:

Be it known that I, SIMEON S. JACKSON, a subject of Great Britain, residing at Hyde Park, Boston, in the county of Suffolk, State 5 of Massachusetts, have invented a certain new and useful Improvement in Weft-Replenishing Looms, of which the following is a specification, reference being had therein to the accompanying drawings.

10 The invention relates to bobbin-changing weft-replenishing looms, and more particularly to the means employed in such looms for the control of the shuttle-feelers and transerrer-dogs of the replenishing mechanism.

15 The invention consists in improved means for the purpose just mentioned.

The drawings show, partly in section, certain of the parts of a loom having an embodiment of the invention applied thereto.

Referring to the drawings,—

20 I provide a transmitter-rocker 1, which I mount at the front of a loom, adjacent the controller-rockshaft 2 of the weft-replenishing mechanism. I combine it operatively with the said rockshaft, so that when the weft-detecting mechanism of the loom causes the rockshaft to be rocked in the direction of the arrow near it in the drawings, in order 25 to bring about replenishment of the shuttle on the lay with weft or filling, the rocker is rocked in unison with the rockshaft. I combine it operatively with the shuttle-feeler 3 and the transerrer-dog 4, so that this rocking of the rocker causes the shuttle-feeler to 30 be swung rearward from its normal position represented in the drawings into feeling position, and the transerrer-dog to be swung upward from its normal depressed position 35 shown in the drawings so as to place its rear end in the path of the bunter 5 carried by the lay-beam 6.

The drawings show a shuttle-feeler 3 of the old overhead type, mounted as heretofore 40 upon a pivot 3^a at the inner face of the stationary plate 7 which supports the horizontally extending stud 8 on which the rotary drum D of the magazine or feeder is mounted. It is connected with the transmitter-rocker 1 by means of a connecting-rod 9 that is joined at its rear end to an arm of the shuttle-feeler extending upward above pivot 3^a, and at its front end to an upwardly extending arm 1^a of the rocker.

45 The transerrer-dog 4 herein, as usual in

practice, is combined with a dog-carrier 4^a that is pivotally hung at 4^c upon a downwardly-extending arm 4^b of the transerrer or hammer 4^d. The said transerrer, as usual, is mounted pivotally upon a stud 4^e 60 projecting outwardly from the supporting-stand 7^a fixed upon the loom-frame 10. The usual spring for holding the transerrer in its uplifted normal position is indicated at 4^f. The usual spring applied in connection 65 with the dog-carrier pivot at 4^c, and acting in connection with the said dog-carrier so as to keep the transerrer-dog down in its normal position shown in the drawings, is not shown, but in practice may be applied as 70 heretofore. The transerrer-dog 4 is connected with the transmitter-rocker 1 by means of a connecting link 11 that is joined at its upper end to the dog-carrier 4^a by means of a pivot 11^a, the lower end of the 75 said link having therein a longitudinal slot 11^b in which works a stud or pin 11^c projecting from a downwardly-extending arm 1^b of the transmitter-rocker.

80 The transmitter-rocker 1 is combined operatively with the controlling rockshaft as by means of a rearwardly-projecting finger 1^c of the said rocker, a give-away lever 12 pivoted upon a downwardly-extending arm 2^a of the said rockshaft and having a forwardly-projecting arm which engages with the under side of said finger, a pull-spring 13 that acts downwardly upon a rearwardly-projecting arm of the give-away lever, and a stop 14 carried by the rockshaft. In this 85 instance, stop 14 is formed upon a pad-lever 14^a fixed upon rockshaft 2. The said stop is in front of the upwardly-extending arm 1^a of the transmitter-rocker. With the parts thus combined and arranged, the pull of the 90 spring operates to keep them in their normal positions shown in the drawings. The said pull, by acting on the rearwardly-extending arm of the give-away lever causes the forwardly-extending arm of the latter to bear 95 upwardly against the finger of the transmitter-rocker, thereby keeping the upwardly-extending arm 1^a of the rocker pressed forward against the rear side or stop 14 on pad-lever 14^a. With arm 1^a in contact with the 100 stop 14, the continued pull of the spring, acting through the pivot by which the give-away lever is connected with arm 2^a, keeps the rockshaft 2 turned in the direction opposite that indicated by the arrow, with pad- 110

lever 14^a in contact with the loom-frame or breast-beam. While the controlling rockshaft and the transmitter-rockshaft occupy the positions just described, the shuttle-feeler 5 is kept retracted forwardly in the position occupied by it in the drawings, and the transferrer-dog is kept lowered into its illustrated position.

When the controlling rockshaft 2 is rocked 10 in the direction of the arrow, the tension of the spring acts through the give-away lever against the finger 1^b to cause the arm 1^a to remain in contact with stop 14 so that the transmitter-rocker is yieldingly actuated to 15 rock in unison with the rockshaft, thereby actuating the shuttle-feeler and transferrer-dog so as to swing the former rearward into shuttle-feeling position, and swing the latter upward into the path of the bunter 5 20 carried by the lay. In case the shuttle 15 occupying the shuttle-box 16 on the lay, instead of being fully home within the shuttle-box in proper position for a fresh bobbin 5 to be inserted into the same from the magazine 25 or feeder by the action of the trans- ferrer, should be part-way displaced out of the shuttle-box, *i. e.*, should project far enough from the mouth of the shuttle-box to strike against the end of the shuttle-feeler 30 as the lay swings forward, the forward movement thereby communicated to the shuttle-feeler will act through connecting-rod 9 to turn transmitter-rocker 1 reversely so as to lower the transferrer-dog before the 35 forward movement of the lay has carried the bunter into engagement with the trans- ferrer-dog.

The give-away lever and spring will yield 40 to permit such reverse turning of the rocker and lowering of the transferrer-dog.

I provide for a toggle-like action by means of which the shuttle-feeler, after having been moved rearward into feeling position, will be moved forward as a result 45 of the actuation of the transferrer through engagement of bunter 5 with the trans- ferrer-dog as the lay swings forward. To this end, the parts are arranged so that the normal position of pin 11^c at the lower end of 50 link 11 is located where a line drawn from such pin to the axis around which the trans- ferrer rocks will pass forward of the pivots connecting link 11 to the dog-carrier and the dog-carrier to downwardly-extending 55 arm 4^b of the transferrer. This constitutes a bent toggle-arrangement. Forward movement of the transferrer-dog, etc., due to engagement of the bunter with the trans- ferrer-dog as the lay swings forward, will act, as 60 the transferrer is actuated to transfer a bobbin from the magazine or feeder to the shuttle 15 on the lay, to straighten the tog- gle-arrangement, thereby occasioning a rocking of the transmitter-rocker 1 so that 65 the shuttle-feeler will be moved forward

from its shuttle-feeling position toward its normal position shown in the drawings. The give-away device yields to permit the said rocking of the transmitter-rocker.

The construction, etc., of the parts may be 70 varied more or less in practice.

What is claimed as the invention is,—

1. In a weft-replenishing loom, the combination with a controlling rockshaft having a pad-finger, a give-away lever pivoted 75 upon an arm of the said rockshaft, a shuttle-feeler, and a transferrer-dog, of a transmitter-rocker having an arm engaged by said lever, a link intermediate the rocker and the shuttle-feeler, a link intermediate 80 the rocker and the dog, and a spring acting through the said lever to keep the rocker engaged with the pad-finger, and also acting through the lever and rocker to keep the rockshaft in normal position, with the pad- finger against its abutment, and the shuttle- feeler and transferrer-dog in their normal 85 inoperative positions.

2. In a weft-replenishing loom, the combination with a controlling rockshaft, a give-away lever pivoted upon an arm of 90 said rockshaft, a shuttle-feeler, and a trans- ferrer-dog, of a transmitter-rocker having an arm engaged by said lever, links inter- 95 mediate the transmitter-rocker and the shuttle-feeler and transferrer-dog, and a spring acting through the said lever to keep the rocker engaged with a stop carried by the rockshaft and the rockshaft in normal 100 position with the shuttle-feeler and trans- ferrer-dog in their normal inoperative positions.

3. In a weft-replenishing loom, the combination with a controlling rockshaft, a give-away lever pivoted upon an arm of the 105 said rockshaft, a shuttle-feeler, and a trans- ferrer-dog, of a transmitter-rocker engaged by said lever, controlling the shuttle-feeler and transferrer-dog, and actuated to position them operatively by the turning of the 110 rockshaft, and a spring acting through the lever to keep the transmitter-rocker normally engaged with a stop carried by the rockshaft and the rockshaft itself normally 115 in a position causing the transmitter-rocker to keep the shuttle-feeler and transferrer- dog in their normal inoperative positions.

4. In a weft-replenishing loom, the combination with a controlling rockshaft and a give-away lever pivotally connected there- 120 with, a shuttle-feeler, and a transferrer-dog, of a transmitter-rocker operatively com- bined with said rockshaft by means of said give-away lever, and connecting means be- 125 tween said transmitter-rocker and the shuttle-feeler and transferrer-dog.

5. In a weft-replenishing loom, the combination of a controlling rockshaft and a give-away device, a transmitter-rocker oper- 130 atively combined with the said rockshaft by

- means of the give-away device, a shuttle-feeler operatively connected with said rocker, a transerrer, a transerrer-dog, and connection means between said dog and said 5 rocker having when the dog is driven forward by the lay-bunter and the transerrer is actuated a toggle-like action which actuates the shuttle-feeler toward its normal position.
- 10 6. In a weft-replenishing loom, the combination of a controlling rockshaft and a give-away device, a transmitter-rocker operatively combined with the said rockshaft by means of the give-away device, a shuttle-feeler operatively connected with said 15 rocker, a transerrer, a transerrer-dog piv-
- totally mounted in connection with a depending arm of the transerrer, and a link connecting said transmitter-rocker with the transerrer-dog, said depending arm and 20 link constituting toggle-members operating, when the transerrer-dog is driven forward, to reversely actuate the rocker to cause forward withdrawal of the shuttle-feeler from its feeling position toward its normal position. 25

In testimony whereof I affix my signature in presence of two witnesses.

SIMEON S. JACKSON.
